UNITED STATES PATENT OFFICE.

JOSEPH W. HAYS, OF CHICAGO, ILLINOIS, ASSIGNOR OF ONE-HALF TO GEORGE L. SIMONDS,
OF CHICAGO, ILLINOIS.

PAPER-RULING MACHINE.

No. 874,587.

Specification of Letters Patent.

Patented Dec. 24, 1907.

Application filed March 6, 1907. Serial No. 360,945.

To all whom it may concern:

Be it known that I, JOSEPH W. HAYS, a citizen of the United States, and a resident of Chicago, in the county of Cook and State 5 of Illinois, have invented certain new and useful Improvements in a Paper-Ruling Machine, of which the following is a clear, full, and exact description.

My invention relates to machines for ruling 10 lines on flat sheets of paper, and its object is to afford a convenient and easily manipulated machine for use in offices, for ruling the sheets used in loose leaf systems by which accounts and records are now extensively kept, 15 and which can be easily adjusted and operated by inexperienced help.

A further object of the invention is to enable the bed of the machine to be so presented to the ruling devices so that the work 20 mounted thereon can be ruled with lines extending first in one direction and then in other directions without removing the work from the bed, and yet another object is to permit of the adjustment or removal of the 25 ruling device to enable any number of lines to be made, near together or far apart, according as desired. This I accomplish by the means hereinafter fully described and as particularly pointed out in the claims.

30 In the drawings:—Figure 1 is a side view of my invention. Fig. 2 is a transverse section taken on dotted line 2—2, Fig. 1. Fig. 3 is a plan view showing a portion thereof broken away. Fig. 4 is a detail view showing 35 a side elevation of one of the ruling devices.

In the drawings A represents a suitable base-plate of wood or other material, which is provided with parallel channel tracks a, a, that are suitably secured upon its upper surface 40 parallel and adjacent to its longitudinal side edges. B represents a longitudinally reciprocal carrier comprising a rectangular plate, preferably of metal, which is narrower than the space between the tracks a, a, and is provided with laterally projecting runners b, that consist of flat metal strips, one longitudinal edge of each of which is secured to the under side of carrier B, and the opposite edge of the portions thereof projecting beyond 45 the side of the carrier, are bent downwards and rest in the channels in the tracks a, a. The longitudinal reciprocal motion of this carrier B is limited by means of a suitable stop c secured to and projecting down 50 from the underside of the same near one end,

and by an adjustable post C. This post consists of a bolt the screw-threaded lower end of which enters an inverted T-shape longitudinal groove c' made in the base-plate A, and it has a square nut C' on its lower end 60 within the under cut portion of said groove. Post C can be loosened in the groove c' by turning it in the proper direction and adjusted longitudinally in said groove to whatever point desired. By turning it in the 65 opposite direction so that nut C' will bind the post in any given position its head will intercept stop c and arrest the movement of the carrier towards it.

Supporting and resting upon the carrier 70 B is a bed-plate D, which is, preferably, of the same dimensions as said carrier, and is rotatively connected thereto by means of a centrally located pivotal stud d secured to the underside thereof, which stud enters and 75 is journaled in suitable bearings d' located in the center of the carrier B, substantially as shown. The carrier B is provided with a series of equi-distant holes e, that are intersected by an imaginary circle struck from the center of the pivotal stud d, and bed-plate D is provided with a spring-depressed bolt E, constructed substantially as shown, and located near one edge of the bed-plate, 80 which is adapted to engage said holes e. 85 One end of the bed-plate D is provided with a suitable paper-clamp consisting of one or more spring-depressed pressure-feet F, which are journaled mediate their ends in lugs f secured to and arising from the bed-plate, 90 and have their opposite ends connected by a bar f', by means of which they can be simultaneously manipulated to release the paper from the bed or clamp it thereto.

Near one end thereof, the base-plate A is 95 provided with oppositely projecting L-shaped brackets G, that are located in transverse alinement, and have their upper ends bifurcated to accommodate suitable vertically reciprocal substantially rectangular 100 guide-blocks H, the bifurcations of said brackets being channeled on said inner sides to accommodate and retain said blocks between them. These blocks are kept at the limit of their upper movement, about as 105 shown in Fig. 1 of the drawings, by coil springs h, seated in the crotch of said bifurcations and supporting said blocks. Connecting said blocks H, H, is a transverse rod I, which is, preferably, square in cross-sec- 110

tion, and adjustable longitudinally on this bar I is a series of ruling devices, each of which consists of a perpendicular shaft *j*, the upper end of which is provided with a substantially square head *k*, that has one vertical side provided with a transverse groove or recess of such dimensions that the bar I can snugly fit into the same so that one side will be flush with the vertical surface of the head. 5
 10 Preferably just below where the bar I enters this transverse recess, a thumb-screw *J* is tapped into the head, and this thumb-screw has a barrel of greater diameter than the screw-threaded end thereof, from which a lateral finger *m* projects, which, when the screw is turned projects over the mouth of said transverse recess and clamps the ruling device to the bar. The lower end of the shaft *j* of the ruling device is provided with a 15 circular chamber *K*, which is occupied by a revolving ink-pad *n* which is journaled in the side of said circular chamber, and the lowest segment of said circular chamber is provided with a slot through which the 20 ruling disk *M* revolves and has circumferential engagement with the ink-pad. The ruling disk is journaled between lugs extending down from the mouth of said slot, and if the bar I is depressed sufficiently, 25 these ruling disks will bear upon the paper placed upon the bed-plate and when the carrier is moved longitudinally will draw the lines desired upon said paper. The construction of the circular chamber, the inking 30 pad, and the ruling disk are substantially the same as that described and claimed in my application for patent for typewriter, filed September 24, 1906, Ser. No. 335,900, and I do not wish to be understood as claiming the 35 same herein except in combination with the other hereinbefore described features of my invention.

The operation of my improved machine is substantially as follows: The paper to be 40 ruled is placed upon and clamped to the bed-plate *D* by the spring actuated pressure-feet *F*, and then the bed-plate is moved longitudinally to a position where the point at which it is desired to commence ruling the 45 line or lines, will be immediately under bar I. The bar I is then depressed until the ruling disks bear upon the work, and then the bed-plate is moved longitudinally a distance corresponding to the length of line it is desired 50 to rule; the surface sheet of paper is then removed and the next sheet ruled in the same manner. When it is desired to rule lines on the paper at right angles to the length of the carrier *B*, the bolt *E* is pulled 55 upwards out of the opening *e*, and the bed-plate revolved until the paper is in the proper position to be ruled in the direction desired, whereupon said bolt *E* is released, and shot into the opening *e* under it, and locks the 60 bed-plate in its newly adjusted position. 65

The bed-plate is then moved and the ruling disks will rule the work, substantially as hereinbefore described.

I can, if desired, provide means for depressing both ends of the bar I simultaneously and more equally than when such depression is effected by hand. This consists of a superimposed horizontal bar *O*, the ends of which are downturned and terminate in bosses *o*, *o*, that are mounted on the ends of the bar I next the brackets *G*. This bar *O* bridges the bar I from end to end, and at its center of length is, preferably, provided with a button *P*, or its equivalent, which can be grasped by the hand when it is desired to 70 depress the bar I, and borne down upon so as to distribute the pressure equally on both ends of bar I. I do not desire to be confined to the use of this superimposed bar I, for it can be dispensed with, if desired. 75

What I claim as new is:—

1. A ruling machine comprising a reciprocal carrier having a bearing therein and having a series of openings arranged around said bearing, a bed-plate having a pivotal stud engaging said bearing whereby said bed-plate is rotatively mounted upon said carrier, a bolt carried by said bed-plate and adapted to engage said openings, and a superimposed compressible series of ruling devices adapted to engage the paper on said bed-plate. 90

2. A ruling machine comprising a suitable base-plate, tracks thereon adjacent to the longitudinal edges thereof, a longitudinally reciprocal carrier, runners therefor the outer longitudinal edges of which engage said tracks, a bed-plate rotatively mounted on said carrier, and a superimposed compressible series of ruling devices adapted to engage the 95 paper on the bed-plate. 100

3. A ruling machine comprising a suitable base-plate, tracks thereon adjacent to the longitudinal edges thereof, a longitudinally reciprocal carrier, runners therefor the outer longitudinal edges of which engage said tracks, a bed-plate mounted on said carrier, means for rotatively adjusting said bed-plate on said carrier, and a superimposed compressible series of ruling devices adapted to 110 engage the paper on the bed-plate. 115

4. A paper ruling machine comprising a suitable base-plate, a bed-plate reciprocally mounted thereon, oppositely located brackets secured to and arising from said base-plate, a transverse bar the ends of which are vertically movable in the upper portions of said brackets, a series of ruling devices adjustable on said bar and means for restoring said bar to its original position after it is depressed. 120

5. A paper ruling machine comprising a suitable base-plate, a bed-plate reciprocally mounted thereon, oppositely located brackets secured to and arising from said base- 125

130

plate, a transverse bar the ends of which are vertically movable in the upper portions of said brackets, a series of ruling devices removably adjustable on said bar and means 5 for restoring said bar to its original position after it is depressed.

6. A paper ruling machine comprising a suitable base-plate, a bed-plate reciprocally mounted thereon, oppositely located brackets secured to and arising from said base-plate, a transverse bar the ends of which are vertically movable in the upper portions of said brackets, a series of ruling devices removably adjustable independently of each 10 other on said bar and means for restoring said bar to its original position after it is depressed.

7. A paper ruling machine comprising a suitable base-plate, a carrier reciprocal on said base-plate, a bed-plate mounted on said carrier, oppositely located brackets secured 20 to and arising from said base-plate, a transverse bar the ends of which are vertically

movable in the upper portions of said brackets, a series of ruling devices adjustable on 25 said bar and means for restoring said bar to its original position after it is depressed.

8. A paper ruling machine comprising a suitable base-plate, a carrier reciprocal on said base-plate, a bed-plate mounted on said carrier, means for rotatively adjusting said bed-plate on said carrier, oppositely located brackets secured to and arising from said base plate, a transverse bar the ends of which are vertically movable in the upper portions 35 of said brackets, a series of ruling devices adjustable on said bar and means for restoring said bar to its original position after it is depressed.

In testimony whereof I have hereunto set 40 my hand and seal this 11th day of February, A. D., 1907.

JOSEPH W. HAYS. [L. s.]
